UNITED STATES PATENT OFFICE.

EDWARD AUGUSTUS WEEKS, OF ELIZABETH, NEW JERSEY, ASSIGNOR TO WEEKS, SAWYER & CO., OF NEW YORK, N. Y., A COPARTNERSHIP COMPOSED OF OLIN H. FLEMING, ARTHUR HARRIS, AND EDWARD A. WEEKS.

DESIGN FOR A TEXTILE FABRIC.

Application filed April 28, 1927. Serial No. 21,776. Term of patent $3\frac{1}{2}$ years.

To all whom it may concern:

Be it known that I, EDWARD A. WEEKS, a citizen of the United States, and a resident of Elizabeth, in the county of Union, State of New Jersey, United States of America, have invented a new, original, and ornamental Design for a Textile Fabric, of which the following is a specification, reference being had to the accompanying drawing, forming part thereof.

The drawing is a fragmentary plan view showing slightly more than one repeat of a textile fabric embodying my new design.

I claim:

The ornamental design for a textile fabric substantially as shown.

EDWARD AUGUSTUS WEEKS.
